UNITED STATES PATENT OFFICE.

WILLIAM R. JEAVONS, OF CLEVELAND, OHIO.

TANK AND GAGE THEREFOR.

1,150,122.

Specification of Letters Patent. Patented Aug. 17, 1915.

Application filed August 23, 1912. Serial No. 716,614.

To all whom it may concern:

Be it known that I, WILLIAM R. JEAVONS, a citizen of the United States, residing at Cleveland, in the county of Cuyahoga and 5 State of Ohio, have invented a certain new and useful Improvement in Tanks and Gages Therefor, of which the following is a full, clear, and exact description, reference being had to the accompanying drawings.

10 This invention relates to tanks and gages therefor.

While some of the features of construction are of universal application, the invention disclosed herein is particularly well 15 adapted for tanks associated with and forming part of the construction of oil stoves and serving to supply oil to the burners thereof.

The general objects of the invention are 20 to produce a tank and gage of this character which are extremely simple in construction, inexpensive of production, but, nevertheless, of great efficiency in operation.

A further object of the invention is to 25 combine a gage with a tank of this character in such a manner that the gage may be firmly and unyieldingly supported and be protected against breakage.

Still further objects of the invention will 30 be set forth hereinafter in connection with the detailed description of the particular embodiment disclosed in the drawings hereof, wherein—

35 Figure 1 represents an end elevation of a tank having my gage applied thereto; Fig. 2 a central vertical sectional view through a tank and gage such as shown in Fig. 1, illustrating the manner in which the gage is supported within the end of the tank; and Fig. 40 3 a sectional detail of one of the caps or heads by which an end of the tank is closed, showing the manner in which the gage may be assembled within such head or cap.

45 Describing by reference characters the various parts illustrated herein, 1 denotes the cylindrical wall of a tank for an oil stove, this shape (cylindrical) being that most ordinarily employed for the tanks of such stoves. One end of the tank is closed 50 by a cap or end piece 2, of ordinary construction, such cap or end piece being seamed onto the adjacent end of the tank wall 1, as by means of the curled edge 3 inclosing the outwardly flared end 4 of the wall 1, the parts being soldered together. The cap for the opposite end of the tank,

however, is especially prepared in order to adapt it for attachment to the end wall and at the same time serve to support the gage in proper operative relation thereto. The 60 cap last referred to comprises a circular end wall 5 of considerably less diameter than the internal diameter of the cylindrical wall 1. The wall 5 projects inwardly from the cylindrical wall 6, the latter wall extending 65 substantially parallel with the wall 1 and forming with such wall an annular space 7. At its outer end, the cap comprising the walls 5 and 6 is flared outwardly, as shown at 8, and is seamed onto the adjacent end of 70 the tank wall 1 in the same manner as the cap 2 is secured to the opposite end of the tank wall, the curled edge 9 on the outer end of the cap inclosing an outwardly projecting flange 10 formed on the end of the wall 1. 75 By this construction, it will be apparent that the cap which is opposite the cap 2 has its major portion, and particularly the wall 5 thereof, inset or recessed with reference to the end of the tank wall 1. This results in 80 providing a space within and protected by the overhanging end of the tank wall 1, and within this space the gage is located.

The gage proper comprises a tube 11 of glass, or similar transparent material, the 85 ends of which are supported within sockets 12 and 13. These sockets are exactly identical except that the socket 12 has an elongated reduced neck 14 while the socket 13 has a neck 15 which is relatively short as 90 compared with the neck 14, although it is also reduced in diameter. Each socket is provided with a flange 16 against which the adjacent end of the tube 11 is adapted to abut. It will be noted that each socket is of 95 considerably greater diameter than the external diameter of the tube 11, thereby providing an annular space surrounding each end of the tube 11, this annular space being adapted to receive a packing. For this 100 packing, I prefer to employ lead, which is inserted in place and is then tamped or pressed into the space between the socket and the adjacent wall of the tube 11, thereby forming a tight and non-leaking joint, as 105 indicated at 17.

Reference has been made heretofore to the fact that the neck 14 is longer than the neck 15. The purpose of making these necks of unequal length will be apparent from an 110 inspection of Fig. 3, wherein the gage is shown as being assembled within the cap 5,

6, 8. The neck 14 will be of such length as will enable the bottom of the neck 15 to be slipped into place within the flange 6 and brought into line with the opening provided for its reception in such flange. When the gage is lowered, the bottom wall 16 of the lower socket can rest upon the flange 6 while sufficient of the neck 14 will project through the opening provided therefor in the opposite portion of the flange 6 to form an anchor for this end of the gage and permit the necks 14 and 15 to be soldered in place. It will also be noted that the diameter of the gage end of its sockets 12 and 13 is such that, 10 when assembled, the gage is entirely within the inset or depressed end of the tank and is completely protected by the projecting end of the tank. It will be noted further that the ends of the gage are in free and 20 open communication with the interior of the tank by means of the annular passageway 7 which is provided between the flange 6 and the wall 1.

In section, in Fig. 2 of the drawing, there 25 is shown the float which it is preferred to employ. This float comprises two cylindrical sheet-metal members, preferably of aluminum, each having an open end and a closed end and arranged to telescope one 30 within the other. 18 denotes the cylindrical wall of one of these members and 19 the closed end of the same. This member is shown as telescoping within the other member, the latter member comprising a cylindrical wall 20 and a closed end 21. When 35 assembled, these two members form in effect a capsule, the walls 18 and 20 of which fit sufficiently close to prevent the passage of liquid therebetween to the air space within 40 the float.

It will be observed that the side wall of the outer member extends the full length of the inner member, so that the end of said wall extends as far as the closed end of the 45 inner member. With this arrangement of parts, there can be no passage of liquid through the space between the walls of the two members. This result might occur through the cooling and consequent contraction 50 of the air within the float, which contraction would tend to "suck" in the liquid. If the annular space between the walls 18 and 20 were short, liquid might work through this space and sink the float.

55 From the foregoing description, it is believed that the operation of the device will be clear. Owing to the free communication of the ends of the gage with the tank, through the necks 15 and 14 and the annular space 7, the liquid will stand at the same level in the tank and in the gage. The float 18—21 will rise and fall with the liquid in the gage and will indicate the height of the liquid in the tank. The gage itself is particularly simple of construction, but is of

marked efficiency. The manner of connecting the gage with the tank insures adequate protection of the gage and a permanent, rigid connection with the tank. Furthermore, the manner of constructing the gage 70 and of assembling it in connection with the tank prevents any leakage of liquid either around the necks 14 and 15 or between the flanges 12 and 13 and the ends of the tube 11.

Having thus described my invention, what 75 I claim is:

1. The combination, with the side wall of a tank, of an end having opposed inwardly projecting portions spaced from the side wall, and a gage entirely within the inwardly projecting portions of the end and communicating with the tank through such portions. 80

2. The combination, with the side wall of a tank, of an end closure for said tank, said end closure having an inwardly directed cylindrical flange spaced from the side wall so as to form an annular chamber or recess therewith, and a gage within such flange and having its ends mounted therein and communicating with the annular chamber or recess, said gage being entirely within the space defined by the flange. 85

3. The combination, with the wall of a tank, of an end closure for said tank, said closure having an inwardly directed flange spaced from the wall so as to form a chamber or recess therewith, and provided with vertically opposed openings in said flange, and a gage within such flange and having necks of unequal length inserted into said openings and communicating with the chamber or recess. 90

4. The combination, with the wall of a tank, of a cap fitted thereto and having vertically opposed inwardly projecting portions spaced from the wall and provided each with an opening, and a gage entirely within the cap and having its ends communicating with said openings. 95

5. The combination, with the side wall of a tank, of an end cap therefor having an inwardly projecting flange spaced from the side wall and having an end closure at the inner end of such flange, and a gage within such flange and having necks projecting through the flange and communicating with the space formed between the flange and the side wall of the tank. 110

6. The combination, with the side wall of a tank, of an end closure therefor, said closure comprising a flange provided with opposed openings and projecting inwardly from the end of the side wall and spaced therefrom and a substantially circular plate at the inner end of such flange, and a gage located within such flange and having necks projecting through the opposed openings in said flange, and each communicating with the space between the flange and the side 115 120 125 130 135 wall of the tank. 140

wall, one of said necks being longer than the other.

7. The combination, with the wall of a tank, of a closure therefor, said closure comprising vertically opposed inwardly projecting portions provided with opposed openings and spaced from the tank wall and a plate at the inner ends of such portions, and a gage located within such closure and having necks projecting through the openings in such inwardly projecting portions and communicating with the interior of the tank, one of said necks being longer than the other.

15 8. The combination, with the cylindrical wall of a tank, of an end wall comprising a cylindrical flange of considerably less diameter than the diameter of the tank wall and a cap or closure at the inner end of the cylindrical flange, and a gage within the flange having its opposite ends connected with the flange and communicating with the space formed between the flange and the tank wall.

9. A gage for the purpose described comprising a tube of transparent material, a socket for each end of said tube, each socket having a wall surrounding and spaced from the wall of the tube, a flange at substantially right angles to said wall and a neck projecting from the flange, and a soft-metal packing tamped or pressed into the space between each end of the tube and the surrounding socket wall and extending nearly to the end of said wall.

35 10. As a new article of manufacture, a gage comprising a tube of transparent material, a socket for each end of the tube, each socket comprising a wall spaced from and surrounding the adjacent end of the tube, an inwardly projecting flange at the end of said wall and a neck projecting from said flange in line with said tube, and a soft-metal pack-

ing tamped or pressed into the space between each end of the tube and the surrounding wall of the socket, the neck of one of said sockets being longer than that of the other.

11. As a new article of manufacture, a gage comprising a tube of transparent material, a socket for each end of the tube, each socket comprising a wall spaced from and surrounding the adjacent end of the tube, an inwardly projecting flange at the end of said wall and a neck projecting from said flange in line with said tube, and a packing in the space between each end of the tube and the surrounding wall of the socket, the neck of one of the sockets being longer than the neck of the other.

12. The combination, with the wall of a tank, of a closure therefor, said closure comprising opposed inwardly projecting portions provided with openings and spaced from the tank wall and a plate at the inner ends of such portions, and a gage located within such closure and having necks projecting through said openings.

13. As a new article of manufacture, a gage comprising a tube of transparent material, a socket for each end of the tube, each socket comprising a wall spaced from and surrounding the adjacent end of the tube, an inwardly projecting flange at the end of said wall and a neck projecting from said flange in line with said tube, and a soft-metal packing tamped or pressed into the space between each end of the tube and the surrounding wall of the socket.

In testimony whereof, I hereunto affix my signature in the presence of two witnesses.

WILLIAM R. JEAVONS.
